UNITED STATES PATENT OFFICE

ROBERT H. INGERSOLL, OF NEW YORK, N. Y.; CHARLES S. SMITH, OF LANSING, MICHIGAN, AND FREDERIC C. LEUBUSCHER, OF ESSEX FALLS, NEW JERSEY, EXECUTORS OF SAID ROBERT H. INGERSOLL, DECEASED, ASSIGNORS TO ROBT. H. INGERSOLL, INC., OF NEW YORK, N. Y., A CORPORATION OF NEW YORK

RAZOR-BLADE STROPPER

Application filed September 30, 1925. Serial No. 59,615.

This invention relates to razor blade holders for employment during the stropping of the blade.

One of the objects of this invention is the provision of a simple, reliable, and cheaply manufactured device of this type, which is very compact and easily carried. Another object is to make such devices of few parts and of slight encumbrance. A further object is to provide an assembly for such devices which is rigid and affords a firm grip to the hand, but has a guard disposed about the sharp edge of the razor blade so that the latter is prevented from injuring the person of the user or the leather strop. Another object is to provide such a structure in which a safety razor blade may be easily and quickly mounted and dismounted, so that very little time will be necessitated for the stropping operation as a whole. A further object is to provide a positive guide stop for the movement of the guard, so that only the desired angle of blade and strop is attained during the stropping operation.

With these and other objects in view as will appear in the course of the following specification, there are represented on the accompanying drawing three modifications of construction in which,

Fig. 1 is a plan view, with portions broken away, of a preferred form of the device.

Fig. 2 is a side view of the device shown in Fig. 1.

Fig. 3 is a cross-section on line 3—3 of Fig. 2.

Fig. 4 is an end view of the device of Fig. 1, showing it in use upon a strop.

Fig. 5 is a perspective view of the handle section.

Fig. 6 is a corresponding view of the blade holder and guard, with a portion of the guard broken away for greater clearness.

Fig. 7 is a plan view of a modified form of the device.

Fig. 8 is a section on lines 8—8 of Fig. 7.

Fig. 9 is a plan view, with a portion broken away, of a further modified form of the device.

Fig. 10 is a section on line 10—10 of Fig. 9.

Fig. 11 is an end view of the device according to Fig. 9.

The device shown in Fig. 1 consists of a handle member 10 which may be formed by cutting and bending sheet metal or tubing, as shown in Fig. 5. The axial bore hole 11 extends for a considerable portion of the length of the handle 10, and is open for substantially its entire length by a slot 12, which near the outer end and the inner end of the bore hole 11 is widened by the notches 13—13 and 14—14, which are disposed in pairs opposite to each other. The portion of the handle 10 which is not drilled for the bore hole 11 is knurled on the exterior as shown at 15, to afford a better grip for the fingers during the operations of stropping and of placing and removing the blade and guard in the handle section.

The blade holder consists of a sheet of metal which is folded upon itself, so that the two ends 16, 16^a lie parallel for a considerable distance, and the folded central portion 19 of the blade holder embraces a sleeve 17.

This sleeve 17 is carried upon the ends of a bent wire guard 18. This guard has its ends within the sleeve 17, and is therefore substantially a closed loop.

The two ends 16, 16^a of the blade holder are designed to have a slight resiliency with regard to each other so that they spring apart when in the position shown in Fig. 6. Intermediate the roll 19 of the blade holder, which surrounds the sleeve 17, and the two ends of this sheet, the two end portions of the sheet flare outwardly as shown at 20. The thickness across the outside surfaces of the sheet at 20—20 is made slightly greater than the thickness of the slot at 12, so that when the handle 10 is slid onto and over the guard 18 and the blade holder 16, 16^a the guard will slide freely in the slot 12; but the blade holder 16, 16^a will be compressed by the engagement of its surfaces 20—20 with the walls of the slot 12, and the outer edges 16, 16^a of the blade holder will be forced toward each other to clamp a safety razor blade B between them, as shown in Figs. 1 and 3.

In operation, when it is desired to sharpen a safety razor blade, the blade is forced be-

tween the two rebent portions 16, 16^a of the blade holder, the guard 18 is brought substantially into the plane of the blade, and the handle 10 is slipped over the guard 18, thus compressing and clamping the ends 16, 16^a of the blade holder and the razor blade B tightly together and holding the latter in position. It will be observed that in this way any flat razor blade may be held in one and the same device. The stropping operation is accomplished in a normal manner, with the added advantage that the razor blade may be turned over its edge in reversing at the end of a stroke without possibility of damage to the strop. During this stropping operation, the guard 18 shifts automatically from side to side of the blade as shown in Fig. 3 in the two dotted line positions, by virtue of its contact with the strop and the natural twisting movement given to the handle 10 during the operation of stropping.

After the blade has been stropped to the desired extent the guard 18 and the blade holder 16, 16^a are slid out of their position within the hollow handle 10, and the blade may be pulled out of the holder.

It is particularly pointed out that this preferred form consists of three members: a one-piece rigid handle with a slot in one side thereof; a one-piece resilient blade holder which slides into the rigid handle, and is clamped thereby over and about the razor blade; the guard which is permanently mounted in the blade holder and is held there-by against axial movement with regard to the handle, but has a limited oscillatory movement in the handle by virtue of the notches 13—13 and 14—14.

In the modified form shown in Figs. 7 and 8, the handle is made of sheet metal and is curled over to form a hollow tube. This handle 25 is formed with a roll 26 near one end which receives the blade holder, and the adjacent portions of the handle next to this roll 26 are depressed to form the parallel plane surfaces 27, which are bounded at the ends by the flared portions 28 and 29 of the handle 25 corresponding to the notches of the device of Fig. 1. The portions 28 are open at the end of the handle, whereas the portions 29 join in the general run of the grip section of the handle. The blade holder is formed as before of a single strip of metal, with the ends 30, 30^a brought into substantially plane parallel relation, with a flared portion adjacent these ends, of an outer to outer surface thickness greater than the space defined between the two parallel plane surfaces 27 of the handle, and with the roll 31 joining these two symmetrical portions and embracing the guard wire 32, which may rock therein.

The operation in this case is the same as that of the device in Figure 1. The blade holder 30 is compressed between the plane surfaces 27 of the handle, so that it is clamped

upon the razor blade B; and the guard 32 has a limited permissive rocking movement within the flared portions 28 and 29 of the handle 25.

This modified form of the device has the same number of members, with the same functions, as that shown in Fig. 1.

In the modified form of Figs. 9 and 10, the razor blade C is of wedge-shaped section. In this case the greater thickness of the blade and its back edge 40 permits drilling small holes as shown for example at 41 in the end of the blade. The guard 42 is formed of sheet metal or bent wire in one piece and passes around the edge of the blade and carries at its ends the integral journal pins 43 which are received within the holes 41. In this way the blade and its guard are constantly associated with each other, even during the shaving operation, at which time the guard may be thrown backward and out of the way.

When it is desired to strop the blade, it is removed from the shaving holder, and introduced between the folded portions 44, 45 of the stropping device. This handle comprises a single sheet of metal folded into the form

of a tube providing a handle 46 but having the end adapted to receive the guard and blade by bringing the two sides 44 and 45 closer together than the thickness of the blade C at the corresponding points. In this way, the sections 44 and 45 resiliently clamp the blade when the latter is forced endwise between them and hold it against movement. A stud or button 47 is provided in the handle to limit the inward movement of the blade C and its guard 42. The portions 44 and 45 are flared outwardly at their two ends as represented at 48 and 49, corresponding to the notches of the device of Fig. 1, so that the guard 42 in this case has a permissive rocking movement about the axis of the pins 43, limited by its contact with the flared portions 48, 49 so that it may present itself at either side of the edge of the blade.

This modified form of the device consists of the rigid handle, and the blade and guard, which are permanently attached together and are held in the handle without the necessity of a separate blade holder.

The position of the handle, the holder, the guard and the strop in presenting the blade to the strop is shown in Figure 4, which is applicable to any of the modifications. It will be seen that the angle of presentation of the blade to the strop depends partly upon the strop tension; and that the stropping device may be reversed upon the strop by turning the blade over its edge without danger to the strop or the operator (see dotted line position).

It is obvious that other modifications and changes may be made within the structure within the scope of the appended claims.

I claim:

1. In a holder for razor blades for use during stropping, an integral member having a handle formed at one end thereon and a longitudinal undercut groove extending from the other end thereof, said groove having oppositely disposed pairs of notches in its walls near the ends thereof, said groove being adapted to receive by an endwise sliding movement and the walls thereof thereby to effect a resilient clamping of a razor blade in position therein, and a closed guard pivotally mounted at both ends with respect to said razor blade and adapted in the operative position of said blade in said member to have a permissive rocking movement from one side to the other of the edge of said blade between the walls of said respective pairs of notches.
2. In a holder for razor blades for use during stropping, an integral rigid member having a handle formed at one end thereof and a longitudinal undercut groove extending from the opposite end thereof, said groove having oppositely disposed pairs of notches in its walls near the ends thereof; an integral blade holder formed with parallel ends adapted to clamp a flat razor blade between them, said ends being joined by a central section of greater thickness adapted to be slidingly received in the undercut groove and held thereby, and portions formed on said blade holder between said ends and said central portion of a greater normal external separation than the width of said groove, whereby said portions are resiliently compressed in the operation of forcing said blade holder into said member; and a blade guard loosely and permanently pivoted in said blade holder and adapted to slide along in said groove during the movement of assembling, and in the operative position of said blade holder in said member to rock from one side to the other of the edge of the blade, said guard being limited in said movement by the walls of the said notches.

In testimony whereof, I affix my signature.
ROBERT H. INGERSOLL.
